UNITED STATES PATENT OFFICE.

JENNIE S. OLSON, OF HOUSTON, MINNESOTA.

TAILOR'S CHART FOR CUTTING GARMENTS.

SPECIFICATION forming part of Letters Patent No. 325,358, dated September 1, 1885.

Application filed April 16, 1885. (No model.)

To all whom it may concern:

Be it known that I, JENNIE S. OLSON, a citizen of the United States, residing at Houston, in the county of Houston and State of Minnesota, have invented certain new and useful Improvements in Tailors' Charts for Cutting Garments, which are fully set forth in the following specification, reference being had to the accompanying drawings, forming a part hereof, and in which—

Figure 1 is a diagram of the front half of a pattern in which are shown a variety of scales used in practice to give the different points for all kinds of forms and sizes, also a scale for cutting and forming top parts or upper edges of sleeves. Fig. 2 is a diagram of the rear section of a pattern for a garment, in which are shown a variety of scales used, respectively, to give the different points, kinds of forms, and sizes. Fig. 3 is a dart-rule used to give the outline or cut for the various seams, said scale being provided with a variety of scales. Fig. 4 is a rule provided with various curves for the seams in the back, back side piece, sleeves, &c. Fig. 5 is a diagram of a pattern for small sleeves and children's sleeves and necks. Fig. 6 shows a sleeve-rule made on the same plan as the bottom of Fig. 1.

The object of my invention is to construct a chart for cutting garments in which certain scales are laid down corresponding to certain measurements taken on the body of the person, and said scales so placed relatively to each other as to greatly simplify the difficulty of laying out and cutting the several pieces.

The measurements taken are, respectively, first, from center and bottom of waist in front up over the shoulder to the center of the back of the neck; second, the length of waist measured perpendicularly upward from the front at bottom of waist first measured from to a horizontal line run across the bust from under the arms; third, the height of darts measured from the same point as the two preceding measures up to "fullness of bust;" fourth, width of breast between the arms; fifth, measurement around the waist; sixth, measurement around the bust; seventh, measurement taken from the same point as first three measurements up to the front of the neck; eighth, measure around the neck; ninth, measure around the armhole; tenth, length of waist un-

der the arm; eleventh, length of back taken from bottom of waist up to neck; twelfth, length of back taken from same point as the eleventh measurement up to intersection of horizontal line from under arms across back; thirteenth, width of back measured between the arms; fourteenth, measurements for the sleeves.

Like letters of reference indicate like parts throughout the drawings.

In Fig. 1 are shown scales marked, respectively, 1, 2, 3, 4, 5, 6, 7, 8, and 9, of which the first gives the height of shoulder measured from the center front and lower end of the waist, the second gives the bottom of waist in front, the third gives the height of darts from the waist-line, also the position of the front of said dart from the center of the front, the fourth gives the width of breast between the arms, the fifth gives the position of the dart or darts on the waist-line or belt, and the sixth, seventh, eighth, and ninth give the "bust measure."

The scales 1, 2, 3, 4, 5, 6, 7, 8, 10, 11, 12, 13, 14, and 15 are placed on the diagram in relative position where they belong, for the purpose of giving proper measures and curves; but the ninth scale may be moved up and down longitudinally on the diagram without affecting anything; but it must be kept at the proper distance from the line or scale 2 in front.

The 1, 6, 7, 8, and 9 scales relate to bust measurements, and are numbered from 15 to 50. They are located by first cutting a well-fitting pattern for a twenty and thirty-four inch bust, or any other two or more arbitrary sizes, and then dividing equally the spaces between the numbers so found. The front edge, 9c on which the scales 2 and 6 are located, is a straight line, and from this, with the smallest sizes, as a starting point (15 in this case) the point 15 in scale 1 is located, also in the scale 7, both of which extend from the small interior diagram, $d' h^3 h^4$, to the large exterior one, giving the size and shape for the neck and shoulder.

The fourth scale is located from the arrowhead d' inward, and marks on a bust a true horizontal line for measuring the width of breast between the arms from the smallest size—four and one-half inches to twenty and one-half inches. The said numbers are just

one-half of the actual measurement. The arrow-head marks by its location both the inside seam of the sleeve and the point at which the measure between the arms is taken.

- 5 The eighth scale, also for bust, is located one and one half inch below the lowest point of the armhole and extends horizontally across the figure, and has its two points, 20 and 34, located as above explained for the 10 first and seventh scales, and is divided in the same way; but at the point 35, instead of continuing straight across, it bends downward and extends to its proper point in the small diagram a' , for the purpose of avoiding the 15 confusing of the points marked on the cloth with the points marked for "width of breast." In this way the shape and position of the arm-hole are properly marked by this scale, and also the point a^2 is located by extending a 20 ruler across from the horizontal part of this scale until it intersects the front line, and from said point a^2 the length of waist-front is measured. The first practical figure is 4 below it.
- 25 The ninth scale is obtained in the same manner as the first, sixth, seventh, and eighth, and of course the point measured from it locates the distance out of the lower end of the line f .
- 30 There are two parallel scales marked 9, placed about four inches apart. They may together be moved up or down from the arm-hole without affecting anything, as they give the width of the bottom of the waist—the 35 lower one for grown people and the upper one for children. They measure from the front edge, as the other scales.
- 35 The length of the side seam is marked on the scale f' , which begins at the point o on the 40 line of the eighth scale; or it may be marked from the star marking the beginning of the scale f on the line of the side seam and the width out on the ninth scale, and at the point where they intersect is the point where the 45 bottom of the waist and side seam intersect. From said intersection up to the point of the star, the position of which is found by the eighth scale, is the line of the side seam. Said point of intersection is found from the 50 tabulated measurements of the body, and will fall on some one of the holes on the intersection of the lines $f^2 f^3$. The points of intersection of the lines $f^2 f^3$ are pierced with holes, which points are found as follows, viz:
- 55 If the measure around the bust is given as thirty-four inches, place a pencil in hole 34 on lower scale 9 for grown persons. Then find what the measure under the arm is—say, eight inches. Find this on the scale f' , and 60 run across on the horizontal line 8 until opposite the pencil. Then put the pencil up or down into that hole. There are also two horizontal rows of figures, $f^4 f^5$. These, for children, are the same, and are placed vertically 65 opposite to the corresponding bust-numbers, as shown in the scale f^4 and its scale 9. Said figures are located from the same patterns

that all the other scales described have been—viz., the twenty and thirty-four inch bust-numbers already mentioned, and measured as 75 follows for the above-size thirty-four inches bust, viz: from the front edge to said number on the scale 9 is eleven and one-half inches, and from the line f^7 , pierced with holes on the true line of the back of Fig. 2 to the vertical line 34 of the scale f^6 , is three and one-half inches. These two numbers are added together and doubled. Their sum gives the whole circumference of the waist—thirty 80 inches. This number is placed vertically opposite the number 34 on said scale 9. All other numbers in said scale are ascertained in the same way.

The scales b , c , and c' are for the size of neck, and begin with the smallest desired size—viz., 85 six inches. Said size is divided into three spaces, of which two spaces of two inches each are given to the two front pieces and two spaces of one inch each to each of the back pieces, making together the circumference of the neck, six 90 inches, between which spaces the scales begin to number with the size 6, respectively, as shown. The abutting scales b are spaced one-eighth of an inch for each unit of measure, the scales c are spaced nine thirty-seconds of an 95 inch for each unit of scale, and the scales c' are spaced three thirty-seconds of an inch for each unit of scale, of which each has twenty units.

To cut out a neck of any size—as, for instance, thirteen and one-half inches—place the number $13\frac{1}{2}$ at the top or point obtained from scale 1 by measuring up from the lower end of the front of waist-line. Mark the point at or nearest the end of such distance—as, for example, say that the length to back of neck over shoulder from said point was nineteen inches, the neck-size thirteen and one-half inches. Then first look on scale c' and find the distance in inches corresponding to said 105 size. The nearest size is found to be one and three-quarter inch. Deduct this number from nineteen inches. This gives seventeen and one-quarter inches measured from the lowest point of the waist-front for height of 110 shoulder-seam, which is marked through the nearest hole in scale 1. Also mark a point at the hole of the bust-measure (in this case number 34) on scale 6. The length of waist-front is measured eight and one-half inches, 115 and the second length waist-front, being thirteen inches, is measured from this lower point up in a straight line through the point made on scale 6, and this distance marked. This gives the lower point of the neck. The mark for 120 size of neck ($13\frac{1}{2}$ of scale c) is now placed on the point marked in scale 1, and the curve of the neck moved back or forward until it touches the point measured from the bottom of waist, (thirteen inches.) It may coincide 125 with the number $13\frac{1}{2}$ on the scale b . If it falls back of the straight line, the point $13\frac{1}{2}$ on scale b is marked, and the straightest edge of the point of the dart-rule, Fig. 3, is used from 130

the point of the dart to the front line of neck, so as to curve gradually into the front line the point which falls at the end of said thirteen inches. If the corresponding number, 13 $\frac{1}{2}$ 5 inches, does not fall directly upon the front so found, but back of it, as it usually does, a dot is made opposite the number 13 $\frac{1}{2}$ on scale *b* and the curve of the neck drawn with the upper and lower points as guides, as already 10 stated, and from the point or end of the line on scale *b* a line is then drawn down by placing the point of the dart-rule, Fig. 3, on the end of said line and drawing a line down the straight edge of said rule until it intersects the 15 front edge in the easiest manner.

The line *g* is for the top of shoulder, and is made from several patterns, so as to ascertain the proper curve for various shoulders, and is marked at *g'* for long necks and slanting shoulders, for which it is used from that point, being placed on the point obtained from scale 1, 20 and the other end of said line resting on top of armhole-number in scale *d*. If the shoulders are "medium," the point *g''* is placed 25 where the point *g'* was placed before, and if the shoulders are square the point *g'* is placed where the points *g'* and *g''* were placed in point marked from scale 1, and the other end of said lines in either case resting on the point marked 30 on the scale *d* for the size of armhole. For the armhole we have the scales *d* and *e* located, as any one would understand how to do, from the point *d'* each their respective distance 35 for a six-inch armhole, ascertained by actual measurement. The point *d'* is placed approximately near the center of the armhole-curve, and it also marks the end of the breast-measures taken between the arms.

The scale *d* has its units each divided into 40 eleven thirty-seconds of an inch, and the scale *e* has its units divided into ten thirty-seconds of an inch.

The armhole measurement, if given as fifteen inches in circumference, is then formed 45 by marking a point opposite the numbers 15 in each of said scales by laying the point *d'* on the mark given in the scale 4, and turned until the armhole line lies against the point made in the "bust-scale" 7, and then a line 50 is drawn along said armhole-curve up to the point 15 in this case. Then the armhole-curve is again turned on point *d'* as a fixed point until the scale *e* comes in contact with the point marked from the scale 8, and then describe 55 the curve of the armhole to the point 15 of said scale. This completes the armhole of Fig. 1. From the lowest point of the line of the armhole (on scale *e*) is drawn a straight horizontal line, tangent thereto toward the 60 back, of indefinite length.

The point 15 of the scale *e* determines the point for the upper end of the line *f*, which is always a straight line, but may incline in either direction from the vertical, according to the 65 difference in size between the bust and waist. The point for the lower end of said line is ascertained in either of the two scales 9 as pre-

viously described, and through said point and the point 15 in scale *e* is drawn the straight line *f*. 70

The point *f'* (indicated by a star) is the intersection of line *f*, and the tangent to the armhole above mentioned from said point *f''*. The line *f* is continued up about three-quarters of an inch for grown persons, or one inch for 75 very large persons, and only about one-half inch for children, and on the end of said line is placed the outer end of the curved line of scale *e*, and the other part of the curve is brought in contact with the said tangent and 80 a line drawn by said curve. This gives the proper curve for the outer end of the armhole.

The scales *h*, *i*, *i'*, and *j* are for cutting the sizes of sleeves, and are arranged for the smallest size, which is an eight-inch sleeve. The 85 point *i'* is placed in the greatest angle of the curved line *h'*, and on each side of it are placed twenty-four units of space, each one-fourth of an inch apart. Then the blank space *h* measures three inches, and the space *h''* six inches, 90 in all nine inches, which gives one inch over for fullness and seam. The curved line *h'* is made from a well-formed sleeve-pattern.

The scales 10, 11, 12, 13, 14, and 15 give the sizes, for dress-sleeves, from six inches to twenty-four inches, as shown by the figures. They are used by marking for any respective size indicated by the figures, and then moving up the diagram and marking the curve from *h'* to 95 *i* on the cloth. 100

The scale 3 is for the purpose of obtaining the height and position of the darts, and is placed in a diagonal position, so as to make the front dart lower than the back dart. The highest point of the scale is of the same height 105 as the scale 8, and from the highest to the lowest point on the vertical position is just four inches, divided into any convenient portions. The position of the first dart from the front is about two and three-fourth inches to the line *h''*, and of the second dart a like distance back of the first to the line *h'*, which marks the first lines for each dart. The series of numerals on each of the vertical lines gives the width of breast-numbers, and indicate that 110 the dart for all such sizes may be placed on that line. 115

The scale 5 is for the width of space from the front line of side to the front edge of dart. It consists of a rectangular diagram of six vertical lines about one-fourth of an inch apart, and nine horizontal lines about one-half of an inch apart. At the intersection of said lines holes are punched. Said scale is placed about one-half inch below the lower point of scale 3. The 120 numbers 25 30 35 40 50 placed on the vertical lines indicate the size of waist-measure, and show that for the first five units the front edge of dart is placed on the first line, marked 25, the next five units or inches of waist-size for 125 the line marked 30, and so on. 130

The diagram Fig. 2 is the regular pattern for a back piece, and like for the front, the point *k* is located from the point *k'*. From said point

k' the scale f^7 is made, which corresponds to regular measures in inches taken on the person from the point k . The line of holes f^7 is located about half an inch inward from the straight line to allow for the slant of the waist. The scale 2 on this diagram is used to give the height at the neck measured from the waist-line up, which is measured in inches on the figure or diagram, and marked at the hole opposite said measure. The scale 2 is made by measurements from a 20 and 34 size bust, as explained for Fig. 1, as are also scales 2, 3, 5, and 6, and scale 4 is obtained for the width of back like scale 4 of Fig. 1 for the width of breast. Scale 3 locates the point k^2 —as, for instance, a thirty-four inch bust-measure gives the point 34 of scale for the point k^2 . Scale 4 locates the width of back from the measure across the width of back, and locates the point k' for width of back by marking through the hole corresponding to the measured size. Scale 5 locates the point k corresponding to the measured bust size—as, for instance, a thirty-four inch bust has the mark made in the hole marked 34. Scale 6 consists of a series of horizontal lines or holes, which correspond to as many different lengths of waists. To use this scale, find the given length of back below the point k' , take the line corresponding thereto and pass out until the number corresponding to the bust-measure is found, which mark. This gives the width of the back piece at the waist-line.

Fig. 3 shows the dart-rule, which is formed of a stiff card-board, like all the other patterns, with a point of which one line is more curved than the other, so that either may be used in marking the form of the darts, seams, &c. There are also marked on said figure two dart-scales, one, l , for single darts, and another, l^2 , for two darts, measuring from the points l l^2 , respectively, and are used in connection with the scales 5 and 9 of Fig. 1. In said scale 9 there are two rows of numbers, one of which gives the bust-number, opposite which is a waist-number, from which subtract the waist-number measured. Thus, if the bust-measure is 34, the waist-number is found to be 30 on scale f^4 . Then, supposing that the actual measured size of waist is twenty-five inches, subtract this

from 30, which leaves 5. Now place the points l^2 or l^3 (according to the design of making one or two darts) on the mark made for the first line of the dart from scale 5 in Fig. 1, then mark the point 5 on single-dart scale, and it will be the width of dart. If two darts are to be made, mark the point 5 as many times as said figure is found on the two-dart scale, which is three times, and it will give the width of both darts and space between them.

Fig. 4 shows an irregular piece about one-half of the longest edge of which is straight, and the other half of which represents the curved seam of the back from the armhole to the waist-line. The line of its larger end is for giving the elbow-curve, and the upper line, m , for shaping collars and any other irregular lines for seams. Fig. 5 shows a pattern for shaping the sleeves at the shoulder and neck for children's clothes.

Fig. 6 shows an extra sleeve-rule. It is made on the same principle and used in the same manner as already explained for using same scale at the bottom of Fig. 1.

What I claim is—

1. In a tailor's chart, the diagram as outlined in Fig. 1, and provided with the scales 1 2 3 4 5 6 7 8 9, constructed and arranged substantially as specified.

2. In a tailor's chart, the diagram as outlined in Fig. 1, and provided with the scales 1 2 3 4 5 6 7 8 9, in combination with a diagram as shown in Fig. 2, provided with the parts c k k^2 k^3 f^6 f^7 , substantially as specified.

3. In a tailor's chart, the diagrams as shown in Fig. 1, provided with scales 1 2 3 4 5 6 7 8 9, in combination with the diagram outlined as shown in Fig. 6, provided with the scales h i , substantially as specified.

4. In a tailor's chart, the diagram as outlined in Fig. 1, and provided with the scales 1 2 3 4 5 6 7 8 9, in combination with a rule constructed as shown in Fig. 3, substantially as specified.

JENNIE S. OLSON.
